UNITED STATES PATENT OFFICE

JOHN W. HOMER, OF GREENCASTLE, PENNSYLVANIA, ASSIGNOR TO T. B. WOOD'S SONS COMPANY, OF CHAMBERSBURG, PENNSYLVANIA

BELT TIGHTENER

Application filed August 9, 1930. Serial No. 474,251.

My invention relates to belt tighteners in which there is a pivoted arm carrying a pulley for engaging the slack reach of a belt to tighten it.

5 The object of the invention is to produce a simple, readily made device of this type, in which the whole mechanism can be easily adjusted, angularly, with respect to its support, standard or bracket, and will be operable in any such adjusted position.

The pulley-carrying arm shall engage a lever at each side thereof, with spring means for said arms to urge the levers against stop means and to urge the pulley-carrying arm 15 to its middle position when deviated therefrom to opposite sides of this middle position.

Other details of construction will be hereinafter more particularly described and 20 claimed.

Referring to the drawings, in which like parts are similarly designated—

Figure 1 is a front view of a belt tightener embodying my invention, with the belt contacting pulley shown only in dotted lines.

Fig. 2 is a side elevation.

Fig. 3 is an elevation of the rear end of the main casting, or plate member.

Fig. 4 is a front elevation of a modification where but a single stop is used for the levers.

Fig. 5 is a side view, and

Fig. 6 is an elevation of a modification using a compression and a tension spring 35 for the levers.

Fig. 7 is an elevation, and

Fig. 8 is a side view of a further modification in which two tension springs are used.

Fig. 9 is a detail of a detent for holding 40 the belt tightener in adjusted position.

Referring to Figures 1-3, I have shown a standard 10 provided with split bearing at the top and clamped together by a screw 11 that frictionally holds a main casting or 45 plate member. Any form of standard, or any other means to stationarily hold this member in adjusted angular position may be used.

This member consists of a plate 12 having 50 on its back a cylindrical bearing boss 13 for

insertion in and to be clamped by the bracket bearing. The boss 13 has an integral adjusting extension for the reception of a wrench, and shown of hexagon shape at 14. This plate 12 has on its face two spaced 55 stops 15 and 16.

Journalled in the plate member and preferably passing entirely through the same is a shaft 17. One end of the shaft has a washer 18, and is secured in the member by 60 a cotter 19. The other end of the shaft has secured to it the arm 20 that carries a pulley shaft 21 on which is journalled the belt-tightening pulley 22.

Projecting from the rear of the arm 20 are 65 two spaced stops 23 and 24.

Journalled on the shaft 17 between the pulley arm 20 and the plate 12 are two levers 25 and 26. The lever 25 is provided with an extension 28 normally resting 70 against the stop 16 and movable toward and against the opposite lug 15, while the other lever 26 has a similar extension 27 normally resting against the lug 15 and movable past extension 28 toward and against lug 16. 75

The two levers 25 and 26 are identical but reversed, so that but one casting has to be made for these levers, as will be seen from the drawings. These levers have lugs 29 and 30 that respectively abut against the lugs 80 23 and 24 on the back of the pulley arm 20.

Each lever arm is provided near its one end with a screw-eye 31 and a lock-nut 32, and the ends of a coiled extension spring 33 are hooked in or otherwise fastened to 85 the screw eyes.

The operation of the structure above described is as follows:

The standard 10 being mounted in proper position at the side of the belt to be tightened, the screw 11 is slightly loosened to allow the boss 13 to be inserted in the bearing of the bracket 10, with the pulley resting lightly against the slack side of the belt. A wrench is then applied to the hexagonal 95 boss extension 14, and the plate member with its assembly of pulley, pulley arm, and spring lever arms is forcibly revolved in the bearing of the bracket 10 against the pressure of the belt, thus bringing into action 100

one of the lever arms 25 or 26, which is displaced from its stop 15 or 16, against the spring tension while the pulley is forced against the slack side of the belt. When 5 sufficient tension is exerted the boss 13 is locked in position by tightening the screw 11.

As the belt lengthens and shortens under load the pulley arm 20 swings in accordance with the amount of slackness of the belt 10 taken up by the levers 25 or 26 under the tension of the spring 33.

If the pulley arm swings beyond its normal position, one of the levers, 25 or 26 will 15 yieldingly resist the movement until it is positively stopped by striking its extension 27 or 28 against its stop 15 or 16. The pulley arm is resisted or damped in both directions toward and from the belt.

The structure is such that it may be 20 mounted near either edge of the belt or against either the inner or outer face of the belt without alteration of the construction.

In Fig. 4 a similar construction is shown, but in this form the two stops 15 and 16 and 25 the lever extensions 27 and 28 are omitted, and in lieu of them is a single stop 34 on the plate 12 that projects between the levers 35 and 36 against which one of them strikes to prevent it from moving with the arm when 30 the other lever is moved against the pull of the coil spring 33 by the pulley arm.

Instead of the lugs 29 and 30 integral with the levers, I may use adjustable lugs in the form of set-screws, Fig. 4.

35 When stronger resistances are in question, in lieu of using a plurality of coil springs between the screw eyes at one end only of the levers, I prefer to place a coil spring at each end of the levers, and this type of belt 40 tightener is illustrated in Figs. 5 to 8.

I have shown a bracket 38 in which the plate member has bearing. The plate 12 has a stop 34 between the levers 39 and 40. Each of these levers has laterally projecting 45 lugs 41 and 42 for engagement with the lugs 23, 24 on the pulley arm 20; and each lever has an extension arm 43 beyond the pivot shaft 17. One of these arms is provided with a pin 44 on which one end of a compression spring 45 seats, and the other end of 50 this spring engages an adjustable seat 43^a in the other extension arm 43.

The compression spring 45 urges the extensions 43 apart while the opposite ends of 55 the levers 39, 40 are urged toward one another, assisted by the springs 33.

In this construction the plate 12 is provided with spiral teeth 46 on its periphery and forms a worm wheel with which meshes 60 a worm 47 mounted in ears 48 on the standard or bracket 38. The worm is provided with a head 49 for applying a wrench for turning the worm and by it the plate 12, to angularly adjust the mechanism in the 65 standard or bracket.

In Figs. 7 and 8 the lever extensions 50 and 51 cross one another, with the result that the coil spring 52 is a tension spring, the same as spring 33.

The plate member is, as above stated, frictionally held in its split bearing, which is sufficient for small constructions of belt 70 tighteners, but in the larger constructions I provide a positive detent, which is provided by the worm and worm wheel construction. 75

Another form of simple, positive detent is illustrated in Fig. 9, where the plate 12 is provided with ratchet teeth 53 and is engaged by a pawl 54 mounted on a pivot 55 on the standard or bracket. The pawl has two teeth engaging ends 56 and 57. This pawl will act as a detent for the plate 12 in either direction of angular slip. All that is necessary is to move the pawl 54 on its pivot, so that tooth 56 will cooperate with the ratchet teeth 53. 80 85

I claim—

1. A belt tightener comprising an angularly adjustable plate member, a pulley arm pivoted to the member, pivoted levers engaging opposite sides of said arm, spring means urging the levers against the arm and stop means to detain one lever when the other lever is deflected by the arm. 90

2. A belt tightener comprising an angularly adjustable plate member, a shaft journaled therein, a pulley arm secured to the shaft, two levers pivoted on the shaft between the member and arm and arranged to engage the arm, each lever having an extension, a spring connecting the levers together, means comprising a pair of spaced stops on the member for engaging said extensions to selectively detain one lever and limit the movement of the other lever under 100 the action of said arm. 105

3. A belt tightener comprising an angularly adjustable plate member, a shaft journaled therein, a pulley arm fixed to the shaft, two levers loose on the shaft between 110 said member and arm and which engage the opposite sides of the arm, two spaced stops on said member, an extension on each lever, both extensions projecting between the stops one disposed against a stop and the movement of the other limited by said stop. 115

4. A belt tightener comprising a standard having a split bearing and a screw to clamp the same, a plate member having a plate, a bearing boss and an adjusting extension, a shaft journaled in said member, two spaced stops on the plate, a pulley arm secured to the shaft, two levers pivoted on said shaft whose ends engage opposite sides of the arm, a spring connecting the levers together against the arm, and an extension on each lever extending between the stops. 120 125

5. In a belt tightener, an angularly adjustable plate member, a shaft journaled in said member, a pulley arm secured to said shaft, 130

two levers pivoted on the shaft between said plate and arm, adjustable lugs in the levers for engaging the opposite sides of said arm, a stop on the member extending 5 between the levers and a spring to urge the levers toward the arm.

6. In a belt tightener, an angularly adjustable plate member, a shaft journalled therein, a pulley arm secured to said shaft, 10 two levers pivoted on the shaft and contacting with the arm on its opposite sides, a stop on the member between the levers, a spring between the levers, extensions on the opposite ends of the levers and a second spring 15 between the extensions, both springs urging the levers to the stop and pulley arm.

7. In a belt tightener, an angularly adjustable plate member, a shaft journalled therein, a pulley arm secured to said shaft, 20 two levers pivoted on the shaft and contacting with the arm on its opposite sides, a stop on the member between the levers, a spring between the ends of said levers, crossed extensions on the opposite ends of the levers 25 and a second spring between the extensions, both springs urging the levers to the stop and pulley arm.

8. In a belt tightener a standard, an angularly adjustable plate member comprising 30 a circular plate having teeth on its periphery, a boss on one face for adjustably holding the member in the standard; a shaft journalled in the member, a pulley arm on one end of the shaft, a tightener pulley on 35 the arm, means on the standard engaging the teeth to angularly adjust the circular plate in the standard, a pair of levers loose on the shaft engaging opposite sides of the arm to damp the movement of the arm in 40 either direction, spring means connecting the levers and stop means for the levers to stop one lever as the other lever is moved by said arm.

9. In a belt tightener, a support, an angularly adjustable member carried by said support, means for angularly adjusting said member with respect to said support, means for locking said member in adjusted position, a pair of levers, means for pivotally 50 supporting said levers adjacent said member, means on said member for engaging one of said levers to rotate said lever as said member is angularly adjusted, resilient means connecting said levers, a pivotally 55 supported arm, having a pulley secured thereto spaced from the pivot of said arm, and an abutment fixedly associated with said arm in position to be engaged by the other 60 of said levers.

10. In a belt tightener, a support, an angularly adjustable member carried by said support, means for angularly adjusting said member with respect to said support, means for holding said member in adjusted position, a pair of levers, a pivotal support for 65

each of said levers, means for positively moving one of said levers about its pivotal support as said member is angularly adjusted, resilient means connecting said levers, a pivotally supported pulley arm, said pulley arm having an abutment fixedly connected therewith in position to be engaged by the other one of said levers. 70

In testimony that I claim the foregoing as my invention, I have signed my name hereto. 75
